Primary Examiner — Derrick Holland*Assistant Examiner* — Janice Patyk(74) *Attorney, Agent, or Firm* — The Belles Group, P.C.(57) **CLAIM**

The ornamental design for a bottle, as shown and described.

DESCRIPTION

FIG. 1 is a perspective view of a bottle showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken line portions are included to show unclaimed subject matter only, including the interior surface of the bottle, and form no part of the claimed design.

1 Claim, 6 Drawing Sheets(56)
